Attorney

Peter L. Borsig

Inventor
Hans P. Sorensen

UNITED STATES PATENT OFFICE

HANS P. SORENSEN, OF PORT CHESTER, NEW YORK

SAFETY MEANS FOR GAS APPARATUS

Application filed January 22, 1930. Serial No. 422,651.

This invention relates to new and useful improvements in safety means for gas apparatus, gas stoves, and the like; and it has been an object of this invention to provide a device, which, when applied and properly connected to a gas apparatus, will automatically light the gas, when the latter is turned on, thereby guarding against the waste of gas, and deplorable accidents occurring, when 10 people, and especially children, through mistake or inadvertence happen to open the gas jets by turning the gas-cocks, or when they open for the gas but forget to apply the pilot.

This device, while embodying the principles of my invention in a general manner, as 15 illustrated herein, may, however, be subject to minor modifications.

As the construction of the device is comparatively simple the cost of manufacturing 20 should be proportionately low; thereby assuring, it is thought, a great market for this invention.

With the above and other objects in view, this invention consists of the novel features 25 of construction, combination and arrangements of parts, hereinafter fully described, claimed and illustrated in the accompanying drawings forming parts of this specification, and in which similar characters of reference 30 indicate corresponding parts in all views, and in which:

Figure 1 is a top plan view, showing part 35 of a gas stove with my device attached; Figure 2 is a front elevational view of same, while Figures 3, 4 and 5 are detail views closely illustrating the different parts of my device.

Referring more particularly to the drawings, 40 10 indicates a gas apparatus, which is connected to a feeding gas pipe 11 by means of the tubes 12; the flow of gas being as usually controlled by the gas-cocks 13, while a pilot button 14 serves to light said gas.

To the said gas pipe 11 is attached in a 45 pivotal manner a member, or flat oblong bar,

15; the said bar being connected by means of hinges 16 to clamps 17, which in turn engage the said pipe 11.

On top of the said bar are arranged a number of raised portions, or parts, 18, the said portions having one side, or surface, formed as an acclivity 19, and the opposite side, or surface, as a declivity 20; the portions 18 may be attached to the said bar in any suitable manner, or may be formed integral therewith.

The device or part of it may be made of all metal or of any suitable material.

Below the said bar is loosely arranged a coiled spring 21 made to convey any pressure 60 exerted upon the said bar to the pilot; the said spring may be wound around the pilot, and project above the latter, or it may be formed integrally with a metal plate suitable to be fastened to the pilot button, as shown 65 in Figure 5.

A transversely positioned member 22, terminating at one end in bifurcated sections 23, is turnably attached to the neck of a gas-cock, the said member having the inner surfaces of the said bifurcated sections shaped to 70 fit the said neck, and is adjustably attached to the latter by means of a screw and wing-nut arrangement 24. However, the shape of the said member, and the manner of attaching 75 and regulating it may well be varied.

The member 22 is at the end opposite the said bifurcated sections formed with an angular downwardly projecting section 25; a pointer 26 is pivotally connected to the lower 80 end of the section 25 in such a manner that the said pointer will collapse or fold in one direction only. A spring 27 is connecting the section 25 to the pointer 26 in order to urge the two parts into alignment, as shown in 85 Figures 2 and 3.

The operation of the device is briefly as follows:

Upon turning the gas-cock in order to open 90 for the gas, the pointer 26 of the member 22

will simultaneously ascend the acclivity 19, and thereby exert a pressure upon the bar 15, which pressure by way of the spring 21 will be relayed to the pilot-button, causing the 5 pilot to operate and light the gas. When the gas-cock with the member 22 has traveled a certain distance, of an imaginary circle, the pointer 26 of the member 22 will descend the declivity 20, thereby relieving the pressure 10 upon the bar 15 and consequently discontinue the operation of the pilot.

In closing the gas by a turning movement 15 in the opposite direction the pointer 26 will automatically and gradually collapse upon striking the sloping surface of the declivity 20, as shown in Figure 4, thereby permitting the member 22 and the gas-cock to travel back to the original or closed position without exerting any pressure upon the bar or actuating 20 the pilot.

It is obvious that changes may be made in 25 the form, construction and arrangement of the several parts, as shown, within the scope of the appended claims, without departing 25 from the spirit of the invention, and I do not therefore desire to limit myself to the construction and arrangement shown and described herein.

What I claim as new, and desire to secure 30 by Letters Patent of the United States, is:

1. A device of the class described, comprising 35 an oblong bar, means for pivotally engaging said bar to a gas pipe, a plurality of elevations arranged upon the top of said bar, the said elevations being formed with one surface gradually ascending and the other surface steeply descending, means for establishing contact between said bar and a pilot, a plurality of pressure-exerting members 40 adjustably attached to a corresponding number of gas-cocks for the purpose of actuating said bar by means of the said elevations, the said members each comprising a bifurcated neckportion for connection with a gas-cock, a downwardly extending portion 45 formed upon one side of said neckportion and integral therewith, a hinged portion connected to said downwardly extending portion and adapted to fold in one direction only, substantially as and for the purpose set forth.

2. A device of the class described, comprising 50 an oblong bar, means for pivotally engaging said bar to a gas pipe, a number of angular elevations formed upon the said bar, a spring for establishing contact between 55 said bar and a pilot, a plurality of pressure-exerting members adjustably attached to a corresponding number of gas-cocks and adapted to actuate the pilot by means of the 60 said angular elevations formed upon the bar, the said pressure-exerting members each comprising a bifurcated horizontally disposed neckportion, means for connecting the 65 latter to a gas-cock, a downwardly extending

portion formed upon one side of said neckportion and integral therewith, a hinged portion connected to said downwardly extending portion and adapted to fold in one direction only, and a spring for keeping said hinged 70 portion normally in elongation of the said downwardly extending neckportion, substantially as and for the purpose set forth.

Signed at Port Chester in the county of Westchester and State of New York, this 75 23rd day of December, A. D. 1929.
